UNITED STATES PATENT OFFICE.

LEOPOLD BAUMEISTER, OF BRIDGEPORT, CONNECTICUT, ASSIGNOR TO L.
BAUMEISTER & CO., OF SAME PLACE.

VAPOR-BURNER FOR SOLDERING AND BRANDING IRONS.

SPECIFICATION forming part of Letters Patent No. 317,489, dated May 12, 1885.

Application filed September 12, 1883. (No model.)

To all whom it may concern:

Be it known that I, LEOPOLD BAUMEISTER, a citizen of the Grand Duchy of Baden, residing at Bridgeport, in the county of Fairfield 5 and State of Connecticut, have invented certain new and useful Improvements in Vapor-Burners for Soldering and Branding Irons; and I do hereby declare the following to be a full, clear, and exact description of the invention, such as will enable others skilled in the art to which it appertains to make and use the same.

My invention relates to the class of devices which require to be kept heated while in use—such, for instance, as soldering and branding irons—and the object thereof is to produce an iron which may be readily heated without the use of a furnace, may be kept hot for any length of time, and which may be laid down 20 for a few moments and again used without the necessity of reheating or placing in contact with flame, while at the same time the device shall be simple in construction, economical in cost, and easy to manage. With these 25 ends in view, my invention consists in the construction and combination of parts, as herein-after fully described, and then specifically designated by the claims.

For the purpose of enabling those skilled in the art to which the invention relates to understand and use my improved device, I will proceed to describe the same, referring by letters to the accompanying drawings, forming part of this specification, in which—

Figure 1 is an elevation of a soldering-iron embodying my invention. Fig. 2 is a central longitudinal section of the same. Fig. 3 is an elevation of the burner, full size. Fig. 4 is a longitudinal section of the burner, wick-tube, 40 and wicks, full size. Fig. 5 is an elevation, and Fig. 6 is a section, full size, of the filter in the vaporizer. Fig. 7 is an elevation of the vaporizer, full size. Fig. 8 is a section, and Fig. 9 an elevation, of a blue-flame tip, which 45 may be substituted in lieu of the soldering-iron for plumbers' and jewelers' use; and Fig. 10 is a section of a branding-iron adapted to be attached to the collet in lieu of the outer tube and the soldering-iron or blue-flame tip.

Similar letters indicate like parts in all the figures of the drawings.

A is the handle, ordinarily made of wood.

B is a bulb or reservoir, which holds the benzine or other liquid hydrocarbon from which the vapor is generated. A tube, C, which is 55 rigidly attached to the bulb, extends down through the handle, as will presently be more fully explained.

D is an aperture for filling the bulb, which is closed by thumb-screw D'. A collet, B', 60 threaded both externally and internally, is formed upon the bulb, to which the outer tube E, having perforations e and e', is attached by the external screw-thread. To the opposite end of tube E the soldering-iron F or blue-flame burner G is attached, as shown in Figs. 1, 2, 8, and 9. Attached to the collet by the inner screw-thread is a plug, H, which, owing to its peculiar construction, I term a vaporizer. The inner end—that is to say, the end 70 toward the reservoir—of the vaporizer is provided with a perforated block or plug, H'. This plug is preferably screwed into the vaporizer, and is provided with a funnel-shaped opening, h, at its inner end, for a purpose presently to be explained. At the other end of the vaporizer is another screw-plug, H², with a minute perforation at H³, hardly visible to the naked eye.

Between plugs H' H² is a filter, I. This 80 filter consists of a tube of brass or other metal, the ends of which are closed by rolls i of wire-gauze. Between the rolls of gauze the tube is filled in closely with particles of a solder made of silver, copper, and tin in about 85 equal quantities, as shown in Figs. 2 and 4. The burner K is attached to the outer end of the vaporizer. The burner consists of a tube, K', having perforations k², a cage or coil, K², of platinum wire attached to the outer end 90 of the tube, and a tip, K³, having perforations k³, and open at the top, as shown. I usually split the tube part way down, as shown at x. The tip is held on simply by the expansion of the tube. I usually attach the tube to the 95 vaporizer by means of a flange, k', which engages with a beveled stud, h', on the vaporizer, as shown in Fig. 4. Within the reservoir is a wick-tube, L, which I ordinarily screw onto the outside of plug H'.

I have found it desirable to use two tubular wicks m m', one within the tube, and the other outside thereof.

With the wicks as shown it is a matter of

no consequence whatever in what position the iron is held, as it will work equally well whether held horizontally or either end up. If held with the point of the iron down, the 5 contents of the reservoir will, of course, settle in the end of the reservoir toward the point which has no direct connection with the vaporizer. In this position the benzine or other fluid will feed up the outer wick by capillary 10 attraction until it comes in contact with the inner wick at the other end of the tube. From this point gravity will assist capillary attraction in the inner wick, and the vaporizer will thus be supplied.

15 Within the handle and extending entirely through it is a tube, C, the inner end of which is soldered to the bulb. The outer end of this tube is screw-threaded, both internally and externally. The outer screw-thread engages 20 with a block, N, in the outer end of the handle, and also with a nut, O. This nut has two internal screw-threads, between which is a shoulder, O'; the larger screw-thread extends only part way through it, and is engaged by 25 the external screw-thread of tube C. A rod, P, extends through the nut and tube, and within the inner wick nearly through the wick-tube in the reservoir, where its beveled point P' engages with the funnel-shaped opening 30 h of plug H', which it is adapted to entirely close. The outer end of the rod is screw-threaded, and engages with the inner screw-thread on tube C, and with the smaller screw-thread in nut O. The outer end of tube C is 35 made slightly funnel-shaped to accommodate a packing, Q, which lies between tube C and rod P, and rests against shoulder O' in nut O, which acts to crowd the packing tightly in place, thus rendering the escape of vapor at 40 this point an absolute impossibility.

The operation is as follows: The reservoir is filled with any liquid hydrocarbon—preferably benzine—and rod P screwed up tight to close the orifice into the vaporizer. The outer 45 tube, E, is then held for a few minutes in flame (a spirit lamp will be found most convenient) to generate the vapor. As soon as the outer tube, and with it the burner, becomes thoroughly heated, rod P is turned backward to 50 open the passage into the vaporizer.

The vapor which forms at the surface of the liquid creates sufficient pressure to force it into the wick-tube and through the inner wick. No air is admitted until the vapor has passed 55 through the filter and into the burner-tube, where it is mixed with air before it reaches the coil, and meets another current at the coil, which assists combustion. The two wicks will act to prevent the passage of any appreciable 60 quantity of benzine into the vaporizer, and the filter will allow nothing but the vapor to escape, and that in a thoroughly purified condition, as no solid matter whatever can pass through the rolls of gauze and particles of a 65 solder made of silver, copper, and tin in about equal quantities, which also control the quantity of vapor that can escape. After passing

through the filter the vapor escapes into the burner-tube K' at the minute perforation H³ in plug H². In this tube the vapor is mixed 70 with atmospheric air, which enters through perforations e' in the outer tube and k² in the inner tube. The current of mixed air and vapor then passes to the platinum coil, in which it meets another current of atmospheric 75 air, which enters through the long perforations e in the outer tube, and perforations k³ in the tip. Combustion takes place at the platinum coil, which requires to be heated to white 80 heat before the vapor is allowed to enter the burner-tube. As soon as the current of mixed vapor and air reaches the coil it takes fire. In use a blue flame of intense heat is thrown into the cavity F' in the soldering-iron and out at the openings F². When the blue-flame tip is 85 used the flame passes directly out at orifice G'.

The branding-iron R, (shown in section in Fig. 10,) is heated in the same manner as the other irons, the only change in construction being that the outer tube and arms R' are cast 90 in one piece, which is attached directly to the collet. The outer rim or band R² of the branding-iron is secured to the arms by screws, as shown.

The letters (not shown) are cast upon the 95 bottom R³. The flame acts upon the bottom, and thus heats the letters, but never comes in contact with the letters themselves, so that constant oxidation and wearing away of the letters is prevented.

R⁴ are small holes for the escape of the vapors when the iron is in use.

The materials used are not of the essence of my invention.

In practice I have found it best to make the 105 reservoir and rod P of steel, the reservoir being made in two parts and soldered together, as shown at B². I have adopted the globular form of reservoir on account of its great strength as compared with other forms, which 110 is desirable on account of the pressure of the hydrocarbon vapor when the iron is in use.

The burner, the soldering-iron, and the bottom letters and rim of the branding-iron I make 115 of copper, the burner-cap and outer tube of iron, and the plugs of brass. In use this iron will be found to work without smoke or smell, as the vapor is wholly consumed at the platinum coil. When it is not desired to use the iron constantly, the vapor may be shut off and 120 the iron laid down for fully five minutes. The vapor may then be turned on, and will instantly take fire at the coil.

I am aware that the general arrangement 125 which I have shown of reservoir, tubes, wicks, and iron, a hollow handle, bevel-pointed rod, &c., also the use of strands or a web of platinum wire, is not new, and also that numerous substances have been used as filters for vapor—such as emery, sand, asbestos, broken glass, 130 granules of lead and copper, and brass and iron filings—and I make no claim thereto, but—

Having thus described my invention and referred to the state of the art, I claim—

1. In a vapor-burner, a filter consisting of a tube closed at each end by a roll of wire-gauze or equivalent material, and filled with particles of a solder made of silver, copper, and tin in about equal quantities, as described, and for the purpose set forth.

2. The vaporizer having plugs H' H^2 , and a filter, I, containing particles of a solder made of silver, copper, and tin in about equal quantities, in combination with the tube K' , the platinum coil, and the tip K^3 .

3. A vapor-burner for soldering-irons, consisting of a tube, K' , having apertures through which air is admitted to mix with the vapor, and at its opposite end a platinum coil covered by a tip, the latter having apertures to admit air to support combustion, and an opening at the top through which the flame escapes.

4. The globular reservoir and a filter of a solder made of silver, copper and tin in about equal quantities, in combination with tube K' , the platinum coil, and the tip K^3 , all combined as and for the purpose set forth.

5. In a vapor-burner, plug H^2 , having a mi-

nute orifice for the escape of vapor, the outer tube having apertures e and e' , and the inner tube having apertures k^2 , whereby air is admitted to mix with the vapor, in combination with the platinum coil and the tip having perforations k^3 to admit air at the point where combustion takes place.

6. Plug H^2 , having a minute orifice, and plug H' , having funnel-shaped opening, in combination with filter I, constructed as described, the inner and outer tubes perforated, as shown, the platinum coil, and the tip covering the same.

7. Plug H' , the wick-tube screw-threaded thereto, and the inner and outer wicks, in combination with plug H^2 , a filter, tube E, a platinum coil, and a tip covering the same, as described, and for the purpose set forth.

In testimony whereof I affix my signature in presence of two witnesses.

LEOPOLD BAUMEISTER.
